BRASSIÈRE

Bernice Harman, Flushing, N. Y.

Application November 20, 1947, Serial No. 787,153

1 Claim. (Cl. 2—42)

1

My present invention relates generally to an improved brassière, and more particularly to a novel and highly improved brassière of the type whose respective breast sections are conical or cupped.

Many solutions have been proposed in the past for the problem of designing the ideal brassière. As women generally know, the ideal brassière should provide comfort to the wearer's bosom, and in cases where the breast tissues have not been broken down should preserve the tissues and keep the bust from sagging. Further, in such cases where breast tissues have already broken down and the breasts sag, as is common in frequent child-birth, the ideal brassière should correctly support the breasts and build up and restore the tissues thereof. Finally, the brassière should provide to the wearer, regardless of bust size, a natural and youthful bust line and contour.

In accordance with one object of my present invention there is provided a brassière constructed ideally to provide the various desired characteristics discussed above; the conical or cupped breast pockets of the brassière having central circular openings for accentuation of small busts and minimizing the large bust.

Another object of my invention is to provide a brassière having its respective breast sections provided with central circular openings whose respective diameters are related in a predetermined manner to the bust size thereby to permit the breasts to protrude through the respective openings in a normal and natural manner.

A more specific object of my invention is to provide any suitable and known brassière with respective central circular openings at the breast pockets whereby each breast is permitted to protrude thereby tending to bring to the front all excess side tissues while concurrently lifting sagging tissue to an upward and outward position.

Other objects of my invention are to improve the construction of present-day brassières, and to provide brassières having non-binding central circular openings at the breast pockets thereof which are economically manufactured.

The present invention consists substantially in the construction, combination, location and relative arrangement of elements, as will be more fully set forth, shown in the accompanying drawing.

In the drawing:

Fig. 1 is a front perspective view of my invention applied to a brassière of the "cupped" type illustrating its application to the body of the wearer;

2

Fig. 2 is an inner face view of the improved brassière, shown in Fig. 1, in extended form;

Fig. 3 is a perspective view similar to Fig. 1 showing the application of my invention to a brassière of the conical breast pocket type; and

Fig. 4 shows a portion of the rear face of one of the cups of Fig. 2 to illustrate the manner of providing the inner cup lining.

Referring now to the accompanying drawing, 10 wherein like reference numerals in the several figures denote similar elements, I have shown in Figs. 1 and 3 the manner in which my improved brassière is applied to a woman's bosom, regardless whether the brassière is of the cup type or 15 of the normal cone pocket type. In accordance with the basic concept of my invention any type of known brassière is provided with respective central circular openings at the frontal or breast pocket, sections thereof thereby to permit the 20 breasts to protrude in the manner, and to a degree, indicated in Figs. 1 and 3. I wish it clearly understood that my invention is in no way limited to the specific brassières depicted. The term "cup" or "conical" is intended to apply to any 25 configuration of breast pocket shaped in that manner.

Considering the cup type brassière of Figs. 1 and 2, it may consist of the usual construction except for the modification thereof in accord 30 with my invention. The band 1, made of a suitable brassière fabric, such as satin or batiste is provided with a pair of cup sections 2 and 3. Those skilled in the art of constructing brassières 35 are fully aware of the manner of emphasizing the bust by cup sections. The numerals 4, 5, 6 and 7 denote the respective panels of cup 3 which are stitched to form the cup section. Each panel has, of course, its edges convergent so as to produce the cup, or wide cone, effect desired. The 40 cup 2 is made up in the same manner, and in Fig. 1 the conical shape of the cup 2 is indicated.

The cups 2 and 3 are not completed, or domed, according to my invention. Instead they have 45 respective central circular openings 8 and 9 of substantial diameter. The diameters of openings 8 and 9 are equal, and are so chosen that a substantial portion of the breasts protrude or project through the openings. Thus in Fig. 1, 50 which shows the brassière on a wearer's torso, the breasts 10 and 11 protrude forwardly through respective openings 8 and 9. The ends of the body band 1 are indicated by numerals 12 and 13, and they respectively terminate in eye strip 12' and 55 hook 13'. These attachment devices 12'—13' are

conventional, and may be replaced by any other suitable securing device.

The usual shoulder straps 14 and 15 are provided, as shown in Fig. 2. The numerals 16 and 17 denote the respective lower and upper finish tapes for the inner face of the brassière, as indicated in Fig. 2. The modification in Fig. 3, it will now be seen, differs only in not using cup sections 2 and 3. Instead the breast pocket sections 2' and 3' are conical. Those skilled in the art are well acquainted with the manner of constructing the front panels 2' and 3' to make them generally conical. Here, again, the central circular openings 8 and 9 are of such diameter that breasts 10 and 11 protrude as indicated in Fig. 3. The inner faces of pockets 2' and 3' may be lined, if desired, with a soft material as described in connection with Figs. 2 and 4.

I prefer to line the inner face of each cup 2 and 3 with a soft fabric lining. However, my invention is not restricted to such a lined pocket. Either pocket, in Fig. 1 or Fig. 3, may be lined or unlined. In the latter case simple tape is used to "edge" the circular openings. In Fig. 2, which shows the inner face of the extended brassière, the numerals 20 and 21 denote the respective fabric linings of cups 3 and 2. The binding tapes 22 and 23, each stitched as a U cooperate with the adjacent inverted V of the tape 17 to keep the peripheral edges of linings 20 and 21 in place. The linings 20 and 21 each have a central circular opening which registers with the associated cup or conical opening.

The central lining panel 24 is stitched at its lower edge under tape 16, while its outer concave edges are stitched under tapes 22 and 23. It will be understood that linings 20, 21 and 24 may be secured, as described, to the inner faces of frontal panels 2' and 3' in Fig. 3.

In order to prevent any binding by the central circular openings 8 and 9, there is provided a special method of securing the peripheral edge of the lining opening to the peripheral edge of the cup or conical opening. In Fig. 4 I have shown the cup 3 with the binding tape 17 removed, and the lining 20 cut away to reveal the peripheral edge of opening 9. It will be observed that circular rim 30 of the cup has been stitched at its inner circle to the peripheral edge of the lining opening.

This is readily and simply accomplished by the following method. The lining 20 (this is also true for lining 21) is first cut to the desired shape as shown in Fig. 2. Then the lining is taken wrong side up and layed down on the front face of cup 3, with an overlap circular zone 30, sewing the peripheral edge of the lining opening to the outer circle of zone 30. After the sewing is finished, the entire lining is turned to the inner face of the cup as shown in Fig. 4. In this way there can be no binding effect at the circle of contact between a breast and the opening of the cup. Hence, in my construction the central circular openings have the peripheral cup edges turned back around the opening and lined.

It is to be clearly understood that brassières embodying my present invention are put on and worn in the same manner as any other brassière, except that my improved brassière has characteristics not provided by any cup, conical or other brassière seeking to secure a youthful and natural bust. By the term "conical" I intend to include all cone-like breast pockets, including the "cup" type. My invention is not restricted to any specific brassière construction, material or shape. The linings 20, 21 and 24 may be any suitable soft netting or mesh.

In relating the circular breast opening diameter to the volume of the breast pocket, be it a cone or cup, it will be understood that the size of the brassière will determine the diameter of the central circular opening. What is most significant is that the protrusion of the frontal portion of a breast shall be substantial. In Figs. 1 and 3 I have depicted an ideal protrusion to provide normal, youthful and natural busts. The larger busts, of course, require a larger conical shaped brassière with corresponding larger central circular openings. The small bust will employ small opening diameters. Regardless of the bust size, whether small or extra large and pendant, the central circular openings will be of such corresponding size as to permit the breasts to protrude.

This tends to bring to the front all excess side tissues, at the same time lifting fallen tissues to an upward and outward position. It is emphasized again that the central breast openings accentuate the small bust while minimizing the large bust. There will be no sag where muscle walls are not broken down, and even in the latter case the brassière provides corrective action. Actual wearing experience over a substantial number of months by the applicant warrants the characteristics claimed for the brassière.

What I claim is:

In a brassière having conical or cupped support and molding breast pockets, each pocket being provided with a central circular unobstructed opening of substantial diameter thereby to provide forward protrusion of a substantial portion of the wearer's breasts through the respective openings.
